CLAIM

The ornamental design for a miniature gem weighing scale, as shown and described.

DESCRIPTION

FIG. 1 is a top, front and right side perspective view of a miniature gem weighing scale showing my new design;

FIG. 2 is a front elevational view;

FIG. 3 is a rear elevational view;

FIG. 4 is a left side elevational view;

FIG. 5 is a right side elevational view;

FIG. 6 is a top plan view;

FIG. 7 is a bottom plan view;

FIG. 8 is a top, front and right side perspective view of a second embodiment showing my new design of FIGS. 1-7;

FIG. 9 is a front elevational view thereof;

FIG. 10 is a right side elevational view thereof, the left side elevational view being a mirror image;

FIG. 11 is a top plan view; and,

FIG. 12 is a top plan view thereof.

The broken line showing of a gem and numbers are environmental only and form no part of the claimed design.
